ASH TRAY

Stephen C. Wenta, Boulder City, Nev.

Application April 20, 1953, Serial No. 24,568

Term of patent 14 years

(Cl. D85—2)

To all whom it may concern:

Be it known that I, Stephen C. Wenta, a citizen of the United States, residing at Boulder City, in the county of Clark and State of Nevada, have invented a new, original, and ornamental Design for an Ash Tray, of which the following is a specification, reference being had to the accompanying drawing, forming part thereof.

Fig. 1 is a top plan view of the ash tray, showing my new design; and

Fig. 2 is a front view thereof.
Ornamentation on the bottom of the tray consists of surface markings only.

I claim:
The ornamental design for an ash tray, as shown and described.

STEPHEN C. WENTA.
